UNITED STATES PATENT OFFICE.

FRANK L. WOLVERTON, OF LUXORA, ARKANSAS.

DOUBLETREE.

SPECIFICATION forming part of Letters Patent No. 756,923, dated April 12, 1904.

Application filed January 28, 1903. Serial No. 140,888. (No model.)

To all whom it may concern:

Be it known that I, FRANK L. WOLVERTON, a citizen of the United States, residing at Luxora, in the county of Mississippi and State of Arkansas, have invented certain new and useful Improvements in Doubletrees, of which the following is a specification.

My invention relates to improvements in the construction of doubletrees or similar draft appliances used on wagons, plows, or machines drawn by two or more horses.

The especial objects sought by my improvements are simple and economical construction and the most effective coöperation of the elements utilized, whereby the best results will be attained.

The chief function of a doubletree constructed according to the principles embodied in my invention is to prevent the stronger or better puller in a team from pulling his mate back against the load, and a minor office is to prevent sudden jerks on the vehicle or other load, which result from inequalities or obstructions in the roadway or from one horse starting ahead of the other.

In carrying out my invention I employ a doubletree made in two sections, the inner ends of which are positively connected with each other, so that any movement of one section is necessarily transmitted to the other, and I so construct and arrange the connecting elements that a movement in the forward direction of one section of the doubletree will produce a like movement in the other section.

I also utilize tension or cushioning devices, which *per se* are not new, either in lieu of or in connection with the ordinary stay-chains.

In the accompanying drawings, which form a part of this application, I have shown a preferred embodiment of my invention, reserving the right to adopt the mechanical equivalents of the parts shown to produce like results.

In my drawings, Figure 1 is a plan view of the front portion of a wagon-gear of common construction, to which a tongue is coupled and with which my improved doubletree is connected. Fig. 2 is a view similar to Fig. 1, but showing the parts in operative relation when draft is applied to one section of the

doubletree. Fig. 3 is an edge view, on an enlarged scale, of the central or coupled portions of the doubletree; and Fig. 4 is a perspective view of the parts shown in Fig. 3.

Referring to the details of the drawings, A 55 represents the fore axle of a wagon, B the tongue, and C the fore hounds that connect the tongue with the axle, all of which are of well-known construction. Bolted to the upper side of the rear part of the tongue is an iron plate f' , which is formed with lateral extensions f'' to form a bearing for the doubletree.

The doubletree is formed in two complementary sections D D', each of which is pivotally connected with the plate by pins or bolts c , which pass through suitable openings c' in the doubletree-sections and in the plate and are provided with nuts on the under side of said plate. The inner and adjacent ends of the sections are rounded and are equipped with metal straps d^3 d^4 , one end of each of which is bolted to one section, as D, and the other end to the other section, as D', the arrangement being at the edges of said sections, 75 thus causing said straps to intersect each other and effecting a coupling between the adjacent ends of the sections. It will be understood that the straps are bent to conform to the edge of the section which they embrace and are 80 of more or less flexible material, so that they will yield as the sections assume different relative positions under tension. It will be noted that tension exerted on the free end of either of the doubletree-sections will be communicated to the other section through the medium of the straps and that the rearward movement of inner end of one section will produce a like movement in the corresponding end of the other section, one of said straps serving to 85 pull against the portion projecting inwardly from the pivot pin or bolt and the other strap serving to push against the corresponding portion of the other section.

In lieu of stay-chains I prefer to use the 95 tension devices E, which are of well-known construction and serve to connect the axle with the respective doubletree-sections, as clearly illustrated in the drawings.

The swingletrees F are connected with the 100

free ends of the doubletree-sections in the usual manner, and, if desired, one section of the doubletree may be made long enough to join thereto two swingletrees, thus providing 5 for three horses.

It will be understood that the tension devices E prevent the doubletree-sections from being pulled too far forward at either end, thus limiting their movement and avoiding 10 the possibility of doubling up the straps, and consequent breakage of same.

Instead of a metal strap for connecting the ends of the doubletree-sections I may use a chain, thus increasing the flexibility of the connection or coupling, but otherwise operating 15 in the same manner as the strap.

The construction above described is such that any ordinary mechanic could apply the parts or mend same, and the embracing-straps 20 on opposite edges of the sections serve to strengthen the latter at their weakest part, which, as is well known, is where the connecting or pivot bolt passes therethrough.

Having thus described my invention, what I 25 claim as new, and desire to obtain by Letters Patent, is—

1. A doubletree formed in two sections pivotally mounted independently of each other, and having their contiguous ends connected 30 with each other, the forward edge of one section being connected with the rear edge of the other section, whereby said sections will move

in unison and in a common direction under tension applied to either.

2. A doubletree formed in two sections pivotally mounted independently of each other, and straps connecting the contiguous inner ends of said sections, said straps connecting the forward edge of one section with the rear edge of the complementary section, and 40 adapted to bear on the projecting inner ends of the sections, for the purpose described.

3. A doubletree formed in two sections pivotally mounted independently of each other and having their contiguous ends rounded, 45 and flexible straps connecting the front edge of one section with the rear edge of the other section and fitting over the rounded ends of the other section.

4. A doubletree formed in pivotally-mounted sections, means for positively coupling the contiguous ends of the sections, said means being secured to opposite edges of the respective sections, whereby the forward movement of one section will cause a like movement of the complementary section, and tension devices connected with said sections and adapted to resist their forward movement.

In testimony whereof I affix my signature in presence of two witnesses.

FRANK L. WOLVERTON.
